United States Patent Office.

NATHAN CLOUGH, OF LOWELL, MASSACHUSETTS.

Letters Patent No. 97,049, dated November 23, 1869.

IMPROVEMENT IN COMBINED BUTTER-CUTTER AND STAMP.

The Schedule referred to in these Letters Patent and making part of the same.

To all whom it may concern:

Be it known that I, NATHAN CLOUGH, of Lowell, in the county of Middlesex, and State of Massachusetts, have invented new and useful Improvements in a Butter-Cutter and Stamp Combined; and I do hereby declare that the following is a full and exact description thereof, reference being had to the accompanying drawings, and to the letters of reference marked thereon.

The nature of my invention consists in providing a butter-cutter and stamp combined, whereby butter may be cut and punched in any form, size, and shape of cakes, at the same time stamped with any design desired, at one operation.

To enable others skilled in the art to make and use my invention, I will proceed to describe its construction and operation.

Figure 1 represents a side elevation of my improved butter-cutter and stamp combined.

Figure 2 represents a longitudinal section of the same, showing its construction and operation.

I construct my improved butter-cutter and stamp with a suitable stock, *a*, which is formed of the required size and shape, on one end of which a shoulder is made, for the reception of the cutter *b*, which is formed of tin or other metal, having its sides, both interior and exterior, parallel from top to bottom, so that it will enter the butter, and also allow the cakes of butter to be easily driven from it. To accomplish this, the metal is of uniform or nearly uniform thickness, and quite thin, its shape, size, and form corresponding with the end of the stock *a*, and is firmly secured to the same by means of screws.

Through the centre of this stock *a*, a hole is made, for the reception of the piston *c*, on one end of which is secured the head or stamp *d*, its form, size, and shape, corresponding with the cutter *b*, it being enough smaller that it will operate in the cutter *b*. On this head or stamp *d* is formed or carved any design or figure desired.

Attached to the other end of this piston *c* is the knob *e*, which is so constructed and arranged that it may be removed at any time, in order to aid and facilitate the cleaning of the cutter *b* and stamp *d*.

My improved butter-cutter and stamp being thus constructed, and its several parts adjusted in position, is then ready for use.

The operator places the cutter *b* on the butter to be cut. He then forces the same into the butter, by aid of the stock *a*, until the same comes in contact with the head or stamp *d*. He then forces the head or stamp *d* on to the same, by aid of the knob *e* and piston *c*, which gives the impression on the same as required, corresponding with the design or figure on the head or stamp *d*. The instrument is then removed, taking with it the cake of butter. Then, by aid of the piston *c* and knob *e*, this stamped cake of butter is removed from the cutter *b*, and deposited on a plate with the stamped side uppermost.

I do not confine myself to any particular size, form, or shape of cakes to be produced, as they may be of any thickness desired, by having the cutter *b* lengthened or shortened, and they may be of any size or shape, as the user desires, by altering the size and shape of the cutter *b*, and any design stamped on the same, as may be desired by the operator.

Thus, it will be seen, with the use of my improved butter-cutter and stamp, butter can be cut in any form, size, and shaped cakes, and at the same time stamped with any figure or design desired at one operation, without using a knife, crumbling the same, or touching the same with the hands in the least, thus furnishing butter for the table use in neat and perfect cakes, of any size and shape, and design stamped on the same at a moment's notice, being cheap, durable, and useful.

What I claim as my invention, and desire to secure by Letters Patent, is—

A combined butter-cutter and stamp, composed of the metallic cutter *b*, with parallel interior and exterior sides secured to the perforated stock *a*, in combination with the piston *c* and stamp *d*, substantially as and for the purpose herein specified.

NATHAN CLOUGH.
